UNITED STATES PATENT OFFICE.

LÉON VANHOESENLANDE, OF PARIS, FRANCE.

MOTOR-CAR WINDSCREEN.

Application filed February 12, 1926, Serial No. 87,799, and in France February 23, 1925.

On an open car such a fixture as a wind-screen for passengers riding on the back-seat is justified only if located near enough their faces to afford protection, while an efficient screen so located must not hinder freedom of movement on the part of the passengers either of ingress or of egress.

The object of my invention is to provide a wind-screen that will meet both these requirements.

In order to make my invention more clearly understood, I have illustrated, as examples, embodiments thereof in and by drawings appended hereto and wherein:

Figure 1 is a fragmental plan view of a motor-car fitted with a wind-screen constructed according to my invention;

Figure 2 is a fragmental side view of the car;

Figure 3 is an elevation of the screen as fitted on the car;

Figures 4 to 8 are detailed views on a larger scale.

Figure 4 is a part-sectional side elevation of one of the posts of the wind-screen;

Figures 5 and 6 show constructional details;

Figures 7 and 8 illustrate two positions of the wind-screen;

Figures 9 to 13 illustrate a modification; Figure 9 is a side view and Figure 10 is a plan view thereof;

Figure 11 shows a constructional detail on a larger scale;

Figure 12 is a diagrammatic cross section;

Figure 13 is a fragmental side view of a motor-car fitted with the modified form of wind-screen.

In all the figures the same reference letters and numerals denote the same parts.

Referring to Figures 1 to 6, it will be seen that the screen comprises a metal frame 1 containing one or more glass panels 2; said frame being connected by hinges 3 with two wings 4 which protect from side wind the faces of passengers riding on the back-seat 5 of the car.

Said screen is mounted between said back-seat 5 and the doors 6 of the car, and to the bottom part of the metal frame 1 is attached an apron 7 made of some pliant or flexible material.

Each of the two posts to which the screen is secured is constituted by a central rod 8 over which is rotatably fitted a locking sock-

et comprising an elongated sleeve 9 integral with two cylinders 10, each of which in turn is formed integral with a short semi-cylindrical outer sleeve or shell 11 that covers 60 part of sleeve 9, while leaving, between itself and said sleeve, a space 12 whereinto engages the adjacent end of a jointing lip or flange 13 soldered to each side wall of frame 1, said flange being semi-circular in 65 section (see Figure 5).

For part of its lower length, rod 8 is threaded so that it can be screwed into a sleeve 14, itself secured by any suitable device to the shaped side wall 15 of the car 70 body.

Central rod 8 terminates at its upper end in a square portion 16 having a tapped aperture into which screws a threaded rod 17 rigidly secured to a cap 18; and this cap 75 bears upon a washer 19 on the top part of rod 8 that is formed with a square aperture to receive lug 16.

Vertical maintenance of sleeve 9 is obtained by tightening screen 17 by means of 80 a tool engaging in a hole 20 provided in cap 18.

Sleeve 9 is thus clamped between washer 19 and a shoulder 25' on rod 8.

When the screen is in use—that is to say, 85 when the car is in motion—it is mounted to extend transversely across the car at a slight inclination to the vertical, as illustrated in Fig. 2.

On the car being stopped, and in order 90 to allow passengers riding on the rear seat 5 to get out through one of the doors 6, the screen can be moved out of the way by swinging it around one of its posts into one of the positions indicated by dotted lines in 95 Figure 1. For this purpose, each sleeve 9 is provided with a handle 21 the arms of which, perpendicular to the axis of the sleeve, remain engaged, while the car is under way, in notches 22 and 23, provided 100 in the wall of the jointing flange 13.

In order to get out through, say, the right-hand door, a back-seat passenger takes hold of handle 21, connected to the right-hand post, and makes it describe a part of 105 a circumference, forcing it against wing 4 which has been itself previously pulled inwards (Figure 7).

Handle 21, in passing from position *a* to position *b* (Figure 8), has carried round 110 with it shells 11, thereby completely disengaging flange 13, which, nevertheless, bears

on ledge 10', until heels or spurs 21' of handle 21 have pushed the screen towards the front of the car, this swinging occurring before the hand, which holds the handle can 5 have come into contact with the glass.

The screen then swings around the left-hand post and allows free egress from the car, the screen being then in the position denoted by A in Figures 1 and 2.

- 10 When the car is to start again and the passengers are seated on seat 5, the reverse operation to that described will return the screen to the desired position, flange 13 having been moved by hand into contact with 15 sleeve 9 and handle 21 having next been turned by hand from position *b* to position *a*. Shells 11 then cover the ends of flange 13 and the arms of handle 21 engage in notches 22 and 23.
- 20 While passengers are getting out of the car and in order to keep the screen in position A or in position B so that its slant will not make it return to running position, the apron 7 can be secured to the driver's seat 25 by any suitable means, say, by turnbuttons 24 which engage in openings provided in said apron.

Whenever use of the screen is not required, the two handles 21 merely have to be turned 30 from position *a* to position *b* to permit removal of the whole system, comprising the screen itself, the two flanges 13 and the two wings 4, as well as the rods 8, which latter can be screwed on and unscrewed by means 35 of a spanner purchased on part 25..

I will now describe the device illustrated by Figures 9 to 13.

In the foregoing arrangement, handle 21 was soldered to sleeve 9. In order not to 40 weaken the latter, while being able to lock the wings 4 in open position, handle 21 is replaced, in the device under consideration, by a handle 26 having the form shown in Figures 9 and 10, one such handle being rigidly connected to each of the upper shells 11.

The end of handle 26 has its under surface hollowed and a recess 27 is provided therein. Each of the shutters or wings 4 is fitted, at 50 its upper part, with a spring pressed catch or bolt 28 mounted in a housing 29.

When the car is going to start and the passengers are seated on seat 5, the screen is brought across the axis of the car by being swung from position *c* to position *d* (Figure 55 10), handle 26 being next forced toward the rear of the car. Each of the wings 4 is moved by hand away from the screen body until bolt 28, pushed out by its spring, engages in the corresponding recess 27. The 60 wing is thereby bolted in position, and, to return it afterwards towards the screen, sufficient hand-effort has merely to be exerted to release bolt 28 from recess 27.

Since the screen is not vertical and, therefore, automatically tends to return to nor-

mal position, means have to be provided to lock it while passengers are getting in or out. For this purpose, each of the tubular vertical side members of the frame 1 is adapted to catch in a small hollow lug fixed 70 on each side of the car at the back of the driver's seat. A mere pull will release the screen.

In order better to protect against an oblique head-wind the heads of passengers 75 riding on the back seat of the car, the upper part of the metal frame 1 is connected with a hollow rail 30, the length of which corresponds to the length of glass 2, and within which is housed a spring 31 tending to wind 80 around rail 30 a curtain or awning 32 made of flexible material. The free end of said curtain is secured to a rod 33 which, when wings 4 are kept open by handles 26, is itself locked, some distance in rear of rail 30, 85 by any suitable device, such as a strap 34 fixed to the upper part of each wing and having a lug 35 fitted with a catch or bolt 36 adapted to engage in an opening 37 provided in each end of rod 33. When the car 90 comes to a stop, rod 33 is released from bolts 36, and spring 31 causes curtain 32 to wind or roll up around rail 30. This device constitutes one of the essential characteristics of 95 my invention.

Since the lower part of the screen is at some height above the upper edge of the car body, it is desirable to make apron 7 reach or extend low enough to screen the legs of the passengers on the rear seat 5. For this purpose the lower part of the metal frame 1 is rigidly connected with a rod 38 100 parallel to rail 30, and under which apron 7 passes before extending forward to be hooked to the back of the driver's seat. Rod 38 is arranged below the upper plane of the car body so that no air can rush under apron 7.

In order to protect back-seat passengers against side gusts, the lower part of the frame of each of the wings 4 is provided with a weather-canvas 39 adapted to be removably secured to the side 15 of the car.

Lastly, further protection against axial air-currents is afforded by means of a stout 115 strip 40, made of leather or any other suitable material, the width of which is greater than the spacing between rail 30 and the metal frame to which it is secured either at back of the screen (full lines on Figure 12) 120 or in front thereof (dotted lines on Figure 12), said strip 40 extending the whole length of glass 2 and its free end bearing against rail 30.

As indicated by the arrows on Figure 13 125 denoting wind-directions, passengers riding on the back-seat of an open car are thiswise fully screened.

I claim as my invention:

1. A rear-seat wind screen for motor cars, 130

- comprising a screen body including a glass-holding frame; a stationary post located adjacent each end of the frame; a locking sleeve rotatably fitted on each post; and a coupling member attached to each end of the frame for releasable connection to the adjacent sleeve, whereby said sleeves may be rotated to lock the screen body to both posts, or either sleeve may be rotated to unlock the screen body from the corresponding post to permit it to be swung laterally about the other post as a pivot into a forwardly inclined position to permit free ingress and egress through the adjacent door of the car. 30
- 5 3. A rear-seat wind screen for motor cars, comprising a screen body including a glass-holding frame; a stationary post located adjacent each end of the frame; an elongated locking sleeve rotatably fitted on each post and provided adjacent each end with a semi-cylindrical socket; and a coupling flange extending along and rigidly secured to each end member of the frame for releasable engagement at its ends in said 35 sockets, whereby said sleeves may be rotated to lock the screen body to both posts, or either sleeve may be rotated to unlock the screen body from the corresponding post to permit it to be swung laterally about the other post 40 as a pivot into a forwardly inclined position to permit free ingress and egress through the adjacent door of the car.
- 10 4. A rear-seat wind screen for motor cars, comprising a screen body including a glass-holding frame; a stationary post located adjacent each end of the frame; an elongated locking sleeve rotatably fitted on each post; and a coupling flange extending along and rigidly secured to each end member of the frame for releasable connection to the adjacent sleeve, whereby said sleeves may be rotated to lock the screen body to both posts, or either sleeve may be rotated to unlock the screen body from the corresponding post to permit it to be swung laterally about the other post 45 as a pivot into a forwardly inclined position to permit free ingress and egress through the adjacent door of the car.
- 15 2. A rear-seat wind screen for motor cars, comprising a screen body including a glass-holding frame; a stationary post located adjacent each end of the frame; an elongated locking sleeve rotatably fitted on each post; and a coupling flange extending along and rigidly secured to each end member of the frame for releasable connection to the adjacent sleeve, whereby said sleeves may be rotated to lock the screen body to both posts, or either sleeve may be rotated to unlock the screen body from the corresponding post to permit it to be swung laterally about the other post 50 as a pivot into a forwardly inclined position to permit free ingress and egress through the adjacent door of the car.
- 20 25

In testimony whereof I affix my signature.

LÉON VANHOESENLANDE.
